UNITED STATES PATENT OFFICE.

ELMER E. TAGGART, OF NEW YORK, N. Y.

ACETYLENE-GENERATOR.

No. 902,023.

Specification of Letters Patent. Patented Oct. 27, 1908.

Application filed December 5, 1907. Serial No. 405,228.

To all whom it may concern:

Be it known that I, ELMER E. TAGGART, a citizen of the United States, residing in the city of New York, borough of Brooklyn, in the county of Kings and State of New York, have invented a certain new and useful Improvement in Acetylene-Generators, of which the following is a specification.

The invention relates to means for producing acetylene gas and more particularly to apparatus for use on shipboard.

The object of the invention is to offer a simple, inexpensive apparatus, easily and economically installed and maintained, which shall be efficient and eminently safe in its operation.

The invention consists in certain novel features of construction and arrangement by which the above objects are attained, to be hereinafter described.

The accompanying drawings form a part of this specification and show approved forms of the invention.

Figure 1 is a vertical section partly in elevation, showing the invention as applied in a vessel. Fig. 2 is an elevation of the generator tank and its connections alone. Fig. 3 is a vertical section on a larger scale, partly in elevation, with the funnel-shaped partition omitted showing the means for controlling the delivery of the carbid. Fig. 4 is a vertical section and elevation of a safety device. Fig. 5 is a face view of a portion of such device.

Similar letters of reference indicate like parts in all the figures.

Referring to Figs. 1 to 5 inclusive, A is the hull of a vessel, B is a strong tank fastened securely therein below the water line of the vessel and stationary relatively thereto. The tank has a closed bottom B¹ preferably inclined toward a large pipe B² leading from the tank to the exterior of the hull and controlled by a sea-cock B³. In the upper portion of the tank is a funnel-shaped partition C forming the carbid chamber C to which the charge of carbid is supplied through a filling orifice in the top of the tank closed by the screw-cap C² or other gas tight closure.

The discharge orifice c in the bottom of the partition C is controlled by two vertically swinging gates D D pivoted below the partition, one on each side of the orifice and having oppositely extending arms D¹ D² con-

nected by links D³ D⁴ to an annular float D² in the generating chamber E.

Gas generated by contact of the carbid with the water escapes through the delivery pipe E¹ and branch E² controlled by a cock E³ to the interior of a small gas-holder or pressure regulator F consisting of an open topped casing partially filled with water and containing a bell F¹ within which the branch pipe E² terminates and adapted to rise and sink as the gas pressure varies. From the top of the bell extends a link F² pivoted to a lever E⁴ on the cock E³ whereby the flow from the generator is controlled and the gas passing from the interior of the bell through the service pipe G is automatically maintained at the desired service pressure.

The pipe E¹ is preferably extended to a considerable height and is provided with a descending branch or leg E⁵ serving as a relief pipe connected to the water pipe B² on the sea side of the sea-cock B³ or otherwise leading to the water outside the hull of the vessel.

The operation of the apparatus is as follows:—Assuming the sea-cock B³ to be closed, the screw-cap C² is removed and a charge of carbid introduced, retained by the gates D held in the closed position by the gravity of the float D², and the cap replaced and again tightly secured. The sea-cock is then opened and water enters the tank, rising in the latter until the pressure of the imprisoned air or gas equals that induced by the exterior water and sufficiently to lift the float and release a portion of the carbid; the latter by contact with the water generates gas as usual, the production continuing until the gas pressure is great enough to force down the water level in the tank and through the gravity of the float again to close the gates. Gas thus generated flows through the pipe E¹ and branch pipe E² into the bell F¹ which rises as the service pressure is exceeded and shuts the gas cock E³ until the service pressure again falls. When the pressure of gas in the tank falls the water level again rises and a fresh supply of carbid is delivered, again driving down the water level. The changes thus caused in the volume of water in the tank produce currents in the pipe B² alternating in direction except at such times when the generation is constant; each outflow carries with it vivified water and spent carbid delivered at the mouth of

the pipe by the inclined bottom B^1 of the tank, and each inflow draws a portion of clean water into the tank, thus automatically discharging the carbid residuum and renewing the water.

H is a draw-off cock by which the water level in the generating chamber can be lowered sufficiently to insure the closing of the carbid orifice c in re-charging with carbid after the sea-cock has been shut off, and J is a circular grating or platform secured to the bottom B^1 beneath the opening in the float to receive the carbid as it falls and provide a resting place therefor during decomposition.

K is a cap forming a water seal for the open end of the branch pipe E^2 within the bell F^1 to prevent the return of gas from the bell and service pipe.

The leg E^5 of the pipe E^1 is sealed by water standing therein at the same level as in the tank B and is always open; its function is to provide a harmless escape for gas to the exterior of the vessel if excessive pressures are accidentally developed in the tank through excessive feeding of carbid. The pipe E^1 and leg E^5 are extended above the water line of the vessel so that when the screw-cap C^2 is removed water cannot enter through these pipes and flood the tank.

In order to guard against flooding by inadvertently removing the screw-cap before closing the sea-cock, a safety device for these parts of the apparatus may be employed; a simple mechanism for this purpose is shown, consisting of a chain L from the lever B^4 of the sea-cock to the screw-cap and extending through a lug L^1 on the upper part of the tank having a keyhole-slot l therein. The chain is of such length as to prevent the removal of the cap while the sea-cock is in the open condition, and the slot is so shaped as to permit the chain to be passed therethrough, aided by the hands, when sufficient slack is furnished by shutting off the sea-cock to allow the cap to be unscrewed. The engagement of the chain with the slot holds the sea-cock in the closed condition until the cap is re-applied and the chain again drawn through the larger portion of the slot to supply the slack required to permit the re-opening of the sea-cock.

Other safety or tell-tale means may be employed for this or other portions of the apparatus or by exercising care the apparatus may be operated without them, and modifications of the forms and proportions of the parts may be made without departing from the principle of the invention, the essential features of which are the tank with tightly closed top and open communication from the bottom thereof to the water in which the vessel floats or is submerged.

It will be noted that the tank is secured to the vessel and that the usual floating bell with its water seal is eliminated. The varia-

tions in space required by variations in volume of gas generated are provided by changes of water level in the tank, and each alternate change of water level induces a corresponding flow of water in one direction or the other through the water pipe B^2 . There is no opening through which gas can escape from the generator to the interior of the vessel; the pressure regulator controls the flow to the service pipe and any excess pressure is harmlessly relieved through the pipes leading to the water outside the hull.

Importance is attached to the location of the pipe E^1 relatively to the water level in the tank and the discharge orifice from the carbid chamber. When the supply of carbid is exhausted and the gas pressure reduced by consumption, the water level in the tank will tend to rise to the water line of the vessel unless the sea-cock B^3 be closed; by locating the entrance to the pipe E^1 below the carbid chamber and above a line reached by the water level in its normal fluctuations any further rise covers the end of the pipe E^1 , imprisons the remaining gas in the upper portion of the tank, and can only rise to a level at which the pressure of the compressed gas equals the pressure due to height of water line, and the parts are so proportioned as thus to check the rise before the water reaches the carbid chamber.

It is also important that the branch pipe E^2 extend above the water line to insure against possible flooding of the pressure regulator and service pipe.

The tank will usually relieve itself of excess pressure through the pipe B^2 but if the sea-cock be turned to the shut position while the gates D D are in the act of feeding, the relief pipe E^5 still permits excess gas to escape harmlessly.

I claim:—

1. A floating structure, a tank disposed within said structure and closed at its upper end, a carbid chamber in the upper portion of said tank, means for supplying water under pressure from the water floating such structure to the portion of said tank below said carbid chamber, and means controlled by the constantly varying quantity of water in said tank through such supply for automatically controlling the feed of the carbid to such water.

2. A floating structure, a tank disposed within said structure and closed at its upper end, a carbid chamber in the upper portion of said tank, means for supplying water under pressure from the water floating such structure to the portion of said tank below said carbid chamber, and means controlled by the constantly varying quantity of water in said tank through such supply for automatically controlling the feed of the carbid to such water, the bottom of said carbid receptacle being at all times above the highest

water level in the tank and below the level of the water floating said structure.

3. A tank closed at its upper end, a carbid chamber in the upper portion of said tank, a pipe for supplying water under pressure to the portion of said tank below said carbid chamber, means controlled by the constantly varying quantity of water in said tank for automatically controlling the feed of the carbid to such water, and means exteriorly of the tank for discharging the excess of gas downward through said water-supplying pipe.

4. A floating structure, a tank therein closed at its upper end, carbid supplying means with its discharge end at all times above the highest water level in said tank, a pipe for supplying water under pressure from the water floating such structure to the bottom of said tank and automatically discharging the spent carbid therefrom through said water supply pipe, and means controlled by the constantly varying quantity of water in said tank for automatically controlling the feed of the carbid to such water.

5. A floating structure, a tank therein closed at its upper end, carbid supplying means with its discharge end at all times above the highest water level in said tank, a pipe for supplying water under pressure from the water floating such structure to the bottom of said tank and automatically discharging the spent carbid therefrom through said water supply pipe, and means controlled by the constantly varying quantity of water in said tank for automatically controlling the feed of the carbid to such water and insuring a constantly varying quantity of water in the tank.

6. A floating structure, a tank therein closed at its upper end, carbid supplying means with its discharge end at all times above the highest water level in said tank, a pipe for supplying water under pressure from the water floating such structure to the bottom of said tank and automatically discharging the spent carbid therefrom through said water supply pipe, means controlled by the constantly varying quantity of water in said tank for automatically controlling the feed of the carbid to such water and insuring a constantly varying quantity of water in the tank, and means for automatically discharging the excess of gas through the water supply pipe.

5. A tank, a carbid chamber in the upper portion thereof, a filling orifice for said chamber, a closure for said orifice, a floating structure to which said tank is secured with its lower portion below the water line of said structure, a pipe leading from the interior of such lower portion through said structure to the water exterior thereto, a sea-cock in said pipe, means for delivering carbid from said chamber to the water in said tank, and connections from said sea-cock to said closure

whereby the closing of the sea-cock is necessitated prior to the removal of said closure, and the replacement of the latter necessitated before the said sea-cock can be re-opened.

8. A tank closed at the top, a floating structure to which said tank is secured with its lower portion below the water line of said structure, a pipe leading from the interior of such lower portion through said structure to the water exterior thereto, a sea-cock in said pipe, means for delivering carbid to the water in said tank, a gas delivery pipe from said tank, a pressure regulator in said delivery pipe, and a gas relief pipe leading from the interior of said tank above the water level therein to the exterior of said structure below the water line thereof.

9. A floating structure, a tank therein, a pipe connecting the bottom of said tank to the water exterior of said structure and having therein a normally open valve whereby the exterior water is continuously automatically delivered to and discharged from said tank, and a carbid feed having a discharge opening at all times above the highest water level in said tank and automatically controlled by the varying water level in said tank.

10. A tank closed at the top, a floating structure to which said tank is secured with the lower portion thereof below the water line of said structure, communicating means between the exterior of said structure and the interior of said tank whereby water flows to and from the latter, means for delivering carbid to the water in the lower portion of said tank, and a gas relief pipe extending from the interior of said tank and into the water-supplying means to the water exterior to said structure.

11. A closed tank, a pipe for continuously and automatically supplying water to and discharging it from said tank and removing the spent carbid, a carbid chamber in said tank above the highest water level therein, gates controlling the discharge from said chamber, a float actuated by the constantly varying water level in said tank and pivotal connections between said gates and float, the whole arranged for continuous automatic operation.

12. A closed tank, a pipe for continuously and automatically supplying water to and discharging it from said tank and removing the spent carbid, a carbid chamber in said tank above the highest water level therein, gates controlling the discharge from said chamber, a float actuated by the constantly varying water level in said tank, pivotal connections between said gates and float, the whole arranged for continuous automatic operation, and a pipe leading from a point above the highest water level in said tank to and discharging into the water-supplying pipe.

13. A closed tank, a floating structure carrying the same, a supply pipe for continuously and automatically supplying water to and discharging it from said tank and re-
5 moving the spent carbid, a carbid chamber in said tank above the highest water level therein, gates controlling the discharge from said chamber, a float actuated by the constantly varying water level in said tank, piv-
10 otal connections between said gates and float, the whole arranged for continuous automatic operation, and a pipe leading from a point above the highest water level in said tank to a point above the level of the exterior water
15 floating said structure and thence downward and discharging into the water-supplying pipe.

14. A closed tank, a floating structure carrying the same, a pipe for continuously and automatically supplying water to and

discharging it from said tank and removing the spent carbid, a carbid chamber in said tank above the highest water level therein, gates controlling the discharge from said chamber, a float actuated by the constantly varying water level in said tank, pivotal connections between said gates and float, the whole arranged for continuous automatic operation, and a pipe leading from the tank above the water level thereof and discharg- 25 ing through the water supply pipe into the exterior water. 30

In testimony that I claim the invention above set forth I affix my signature, in presence of two witnesses.
